UNITED STATES PATENT OFFICE.

JUDSON L. THOMSON AND JACOB J. UNBEHEND, OF SYRACUSE, NEW YORK;
SAID UNBEHEND ASSIGNOR TO SAID THOMSON.

SHOE-CLASP.

SPECIFICATION forming part of Letters Patent No. 313,385, dated March 3, 1885.

Application filed October 16, 1884. (No model.)

To all whom it may concern:

Be it known that we, JUDSON L. THOMSON and JACOB J. UNBEHEND, both of Syracuse, in the county of Onondaga, in the State of New York, have invented new and useful Improvements in Spring-Clasps, of which the following, taken in connection with the accompanying drawings, is a full, clear, and exact description.

10 This invention relates to the class of clasps which have a slotted plate interlocking with a tongue hinged on another plate, and a spring arranged to hold said tongue in position for engaging with the slotted plate and for retaining said plate interlocked with the tongue.

15 The object of this invention is to simplify the construction of the clasp, and thereby reduce the cost of manufacture, and at the same time produce a clasp of great efficiency and 20 durability; and to that end the invention consists, first, of a tongue connected to its supporting-plate by a duplex pintle; and, secondly, of a tongue provided with an eye of angular or elongated form in cross-section, in 25 combination with a base-plate having two pintles extending into the eye of the tongue, and held normally apart to receive the impingement of the eye of the tongue when swinging said tongue back and forth on the base-plate, as 30 hereinafter more fully described, and specifically set forth in the claims.

In the accompanying drawings, Figure I is 35 a plan view showing the tongue of the clasp interlocked with the slotted plate. Fig. II is a longitudinal section of the same, with the slotted plate shown by dotted lines. Fig. III is a longitudinal section of the clasp, with the tongue raised from its supporting-plate, or base-plate. Fig. IV is a plan view of the 40 tongue and its base-plate or supporting-plate, showing the tongue in an open or distended position; and Fig. V is a detached plan view of the aforesaid base-plate.

A represents the usual transversely-slotted 45 plate which is to be attached to one of the straps or quarters of the shoe, and is adapted to interlock with the tongue T, hinged to the base-plate B, which is to be attached to the other strap or quarter of the shoe. The base-plate B is provided with a pintle, a, and upon

said plate lies a spring-plate, C, which is either integral with or firmly attached to the plate B, at the rear end thereof, and is provided at the opposite end with a supplemental pintle, a', which is held over the pintle a and normally apart from the same by the deflection of the free end of the spring-plate from the base-plate, as shown in Fig. II of the drawings. The tongue T is provided with a sleeve or eye, e, which embraces the two pintles a a', and is either of angular or elongated form in cross-section, and has its greatest diameter at such an angle to the plane of the tongue that when the tongue lies upon the base-plate B a line drawn across the greatest diameter of the eye 65 e passes vertically through the two pintles a a', which are thus allowed to spring apart from each other, as shown in Fig. II of the drawings; hence the spring is under the least strain when the tongue is closed or swung 70 down upon the base-plate, and inasmuch as this is the condition of the tongue when the clasp is in use it is obvious that both the spring and the pintles are greatly relieved of wear and abrasion. Furthermore, by the employment of two pintles in lieu of a single pintle, as in other clasps, greater strength and 75 durability are imparted to the clasp.

We do not limit our invention to the specific arrangement of one pintle above the other, 80 inasmuch as the disposition of said pintles is susceptible of various modifications—as, for instance, by an upward deflection of the two plates B and C the two pintles become arranged one back of the other, in which case 85 the elongation of the eye e of the tongue would have to be in a direction at right angles to that of the elongation of said eye shown in the annexed drawings.

Our invention also materially reduces the 90 cost of the manufacture of the clasp, inasmuch as the tongue, with its comparatively large eye e, can be easily formed out of sheet-iron, whereas heretofore the tongue was subjected to so much strain as to require it to be formed 95 of steel, and the eye of the tongue was in some instances so small as to render it very difficult to be formed of steel, and entailed great waste of material and labor, owing to the breakage of the plate in bending the same.

In our improved clasp the spring and pintles are subjected to the maximum strain only when the tongue is raised and swung half-way into its distended position, as shown in Fig. III 5 of the drawings, and since the tongue is held in said position only momentarily it is obvious that but little strain is exerted on the spring and pintles.

What we claim is—

- 10 1. The improved shoe-clasp having the tongue connected to its supporting-plate by a duplex pintle, one over the other, as set forth.
2. A spring-clasp comprising a base-plate carrying two pintles sustained yieldingly one over the other and normally apart from each other, and a tongue having an eye of angular or elongated form in cross-section embracing the two pintles.
- 15 3. In a spring-clasp, the combination of two plates lying one upon the other and united at one end, each at its free end carrying a pintle held normally apart one above the other, and a tongue having an eye of angular or

elongated form in cross-section embracing the two pintles, as set forth and shown. 25

4. The combination of the base-plate provided with a pintle, the spring-plate attached to the base-plate and carrying a supplemental pintle over the pintle of the base-plate and normally apart from the same, and the tongue 30 provided with an eye of angular or elongated form in cross-section and standing with its largest diameter nearly at right angles to the plane of the tongue, substantially as shown and set forth.

In testimony whereof we have hereunto signed our names and affixed our seals, in the presence of two attesting witnesses, at Syracuse, in the county of Onondaga, in the State of New York, this 14th day of October, 1884.
